UNITED STATES PATENT OFFICE.

OSCAR D. REDDEN, OF LEROY, TEXAS.

COIN-CONTROLLED PUMP.

1,188,322.

Specification of Letters Patent. Patented June 20, 1916.

Application filed November 2, 1915. Serial No. 59,226.

To all whom it may concern:

Be it known that I, OSCAR D. REDDEN, a citizen of the United States, residing at Leroy, in the county of McLennan and State of Texas, have invented certain new and useful Improvements in Coin-Controlled Pumps, of which the following is a specification.

This invention relates to a coin controlled device for pumping and supplying to a customer a predetermined amount of liquid, such as gasolene, the amount delivered depending upon the size or value of the coin or check deposited.

15 The object of the invention is to provide a pumping device which will be normally locked but which upon the insertion of a suitable coin or check may be unlocked and the pump operated until a predetermined amount of liquid has been made accessible to the customer, with means for automatically relocking the device when the customer ceases to draw upon the supply available to him, and to permit the draining back 25 into the original source of supply any surplus liquid not taken by the customer.

With these objects in view the invention consists of the novel features of construction hereinafter described, pointed out in 30 the claims and shown in the accompanying drawings, in which:

Figure 1 is a side elevation, parts being broken away, and in section. Fig. 2 is a similar view from the opposite side, the 35 parts being in different position. Fig. 3 is a perspective view of the coin controlled mechanism, a casing being removed. Fig. 4 is a transverse section on the line 4—4 of Fig. 1. Figs. 5 and 6 are detail sectional views illustrating coin openings in a shaft.

In these drawings 1 represents a suitable casing placed over or above any suitable source of supply such as a tank or reservoir, and a supply pipe 2 leads from said source 45 of supply, not shown, and upwardly into the casing 1 where it is provided with a suitable check valve 3, and a union 4. From said union said supply pipe continues and opens into the working barrel 5 of a suitable pump provided with a piston 6. From the union 4 there leads a delivery pipe 7 which passes outwardly through a side of

the casing 1 where it terminates in a valve faucet 8 suitably threaded to receive the end of a hose section. The said pipe 7 has also 55 a branch 9 which passes through the casing and carries a spigot 10 from which liquid can be discharged conveniently into a can or bucket. It will of course be understood that the use of the device is not limited 60 to the particular liquid named, as the same mechanism can be employed for the delivery of any liquid adapted to be pumped.

Mounted upon the top of the casing 1 is a second casing 11 which incloses the coin controlled mechanism by means of which the pump is locked and unlocked. This mechanism is shown most clearly in Fig. 3. Mounted upon a suitable base 12 which may also be the top of the casing 1 is a bracket 13 in which is journaled a shaft 14. Said shaft projects through the casing 11 and at its outer end carries an operating handle 15. Within the bracket 13 the shaft is provided with two longitudinal slots 16 and 17, the slot 16 being slightly smaller than the slot 17 and not extending entirely through the shaft, but being in effect a deep groove. The slot 17 however, extends entirely through the shaft and each of said 80 slots is normally in vertical alinement, respectively with coin chutes 16^a and 17^a. The coin chute 16^a is intended to receive a dime which passing through said chute falls into the groove 16. The chute 17^a is designed to receive a quarter, and the said coin falls into but does not pass through the slot 17. Should a smaller coin than a quarter of a dollar be inserted into the chute 17^a it will fall through the slot 17. The 85 shaft is so positioned with respect to the lower ends of the coin chutes that if the slots are not in alinement with the chutes a coin deposited in either one of them will rest upon its edge on the periphery of the 90 shaft until the shaft has been rotated a sufficient distance to bring the slot into position to receive the coin, and as soon as a coin has dropped into proper position in the shaft it will clear the chute.

100 Fixed on the shaft 14 is a double ratchet wheel 18 and a gear wheel 19. Above the shaft 14 is mounted a rock shaft 20 one end of which is journaled in one side of the

bracket 13 and the other end is mounted in a supplemental bracket 21 and is provided with a crank portion 22, which portion carries a pin 23 to which is attached a coil spring 24 the upper end of which is secured to the top of the bracket 13, said spring holding the rock shaft 20 against improper rotation as will hereafter appear. Mounted on the rock shaft is a double pawl 25 which 5 co-operates with the double ratchet 18, and it will be clear that when one member of this pawl is in engagement with one member of the ratchet wheel it will be held in engagement by the pull of the spring 24 on 10 the crank portion 22. And if the shaft 20 is rocked so as to throw the other pawl member toward the ratchet wheel the spring 24 will aid in such rocking movement as soon as the crank portion 22 passes center, 15 and the spring 24 will then hold the other pawl member in engagement. It will also be clear that there can be no reversal in rotation of the shaft 14 without first rocking the shaft 20 so as to shift the pawl 20 members, and normally there is no connection between the two shafts.

The shaft 20 has also fixed upon it a tripping finger 26 which extends downwardly into a position adjacent that part of the 25 shaft 14 having the groove or slot 16 and if a coin or check is in said groove or slot it will strike said finger 26 upon rotation of the shaft 14 thereby rocking the shaft 20 sufficiently to carry the crank portion 22 past center and the pull of the spring 24 will complete the movement and shift the pawl, thereby permitting shaft 14 to freely turn in the opposite direction. For clearness of description the direction of rotation 30 of the shaft to trip finger 26 by means of the coin will be termed a backward rotation of the handle 15. In Fig. 3 I have shown the coin in position, with the tripping action just completed, and the parts in position to permit what will be termed backward or pumping rotation of the handle 15. A finger 27 is also fixed on shaft 20 to be engaged by the coin or check dropping into the slot 17.

It will now be noted that the piston 6 is 35 provided with a plunger rod 28 which rod is in the form of a toothed bar and is in mesh with the gear wheel 19 on shaft 14 normally the piston is at the end of its down stroke and the pawl 25 is in such engagement with the double ratchet that the shaft 14 cannot be rotated so as to lift said plunger, but when the pawl has been shifted by means 40 of a coin so that the pawl occupies the position shown in the drawing backward rotation of the handle 15 is permitted and said rotation causes the gear 19 to move the plunger rod upwardly thereby lifting the piston and drawing a supply of liquid into the working barrel. The check valve 3 prevents 45 its return to the source of supply but in

order to deliver it to the customer it is necessary that there be a downward movement of the piston, and consequently a reversal of direction of rotation of the shaft 14 is necessary. It will also be obvious that the 70 amount delivered will depend upon the amount pumped up and subsequently expelled and this in turn depends upon the movement of the plunger rod 28.

On the base 12 is a bracket 29 in which 75 is mounted a lever 30 provided with a suitable counter-weight 31. A rod 32 is mounted upon one end of the lever 30 and is provided adjacent the shaft 20 with a suitable button 33. The finger 27 is provided with a claw-portion 34 that straddles the rod 32. A rod 35 is also loosely connected at one end to an extension of the finger 27, the upper end of the rod being journaled in a small bracket 36. The rod 35 carries a rotatable stop 37 within the bracket 13 and has at its upper end a laterally extending stop 38. The stop 37 is loosely connected to the rod 35 by means of any suitable form of strap or link 39. Carried by the upper end 80 of the plunger rod 28 is a hinged shoe 40.

When the finger 26 is tripped by a coin the handle 15 can be turned backward as previously explained and the plunger rod 28 is moved upwardly by the gear 19 until the 95 shoe 40 strikes the stop 37 thereby lifting the rod 35 and rocking the finger 27 and the shaft 20 in the direction opposite to which it was rocked when the coin engaged the finger 26. This action reverses the action 100 of the pawl 25 and no further rotation of the shaft 14 in the backward direction is possible. The coin in the meantime has fallen from the groove 16 and has entered a suitable coin receptacle 41. The customer now 105 turns the handle forward and the downward movement of the plunger rod and piston forces the liquid from the working barrel out through the delivery pipe 7.

If the larger quantity is desired and the 110 coin or check is deposited in the chute 17^a the coin will enter the slot 17 and on backward turn of the handle will strike the finger 27 thereby rocking shaft 20 and throwing the parts into position shown in Fig. 3, and the 115 coin will then strike the inner short end of the lever 30 depressing the same and lifting the rod 32, this movement being aided by the counter-weight 31. The upward movement of rod 32 will exert a pull on the strap 39 and will cause the stop 37 to rotate sufficiently upon shaft 35 that it will be out of the path of the shoe 40 and the plunger 28 will be permitted to rise until said shoe 120 strikes a stop 38, thereby pumping a greater amount of liquid into the working barrel, and it will also be understood that the stop 37 may be adjusted along the shaft 35 with respect to the stop 38. When the shoe 40 strikes the stop 38 the rod 35 will be lifted 125 130

thereby rocking the tripping finger 27 and producing the same result as if the stop 37 had been struck. It will be noted however, that when the stop 37 is engaged the claw member 34 simply swings idly along the rod 32, but when said rod is lifted to draw aside the stop 37 the button 33 is brought up adjacent to the claw member 34, and therefore when the rod 35 is lifted by the 10 shoe 40 engaging the stop 38 the member 34 as it swings down will press against said button and will return the rod 32 to its normal position, returning to normal position also the lever 30 and the stop 37, but as the 15 shoe 40 is hinged it can pass the stop 37 on the downward movement.

The above explains fully the construction and operation of the coin controlled parts of the device. But in order to drain back 20 to the reservoir any liquid which might remain in the working valve through failure of the purchaser to draw off the full amount to which he was entitled I provide a drain pipe 42. This is provided with a suitable 25 valve 43 so as to close said drain while the customer is using the pump. To the handle 44 of the valve is connected an operating rod 45 the upper end of which is connected to a post 46 which post carries a 30 suitable hanger 47 that extends out through the casing 11 and a spring 48 will tend to lift the post 46 thereby pulling the rod 45 up and closing the valve 43.

I have already referred to the use of a 35 hose in connection with the faucet 8. A hose section 49 has one end secured to said faucet and when the device is not in use the hose is hung on the hanger 47, and the weight of the same forces the hanger downwardly and 40 brings the valve into open position, and the customer is directed to remove the hose from said hanger when using the device and to replace it when through, and the hose is therefore taken down even if the liquid is 45 drawn out through the spigot 10. Should the customer fail to follow instructions the device will still operate and the only result of failure to remove the hose from the hanger would be the draining back of a 50 small portion of the liquid which the customer would otherwise obtain.

What I claim is:

1. A device of the kind described comprising two coin chutes, a rotatable shaft in vertical alinement with said chutes and provided with a groove registering with one of the chutes and with a slot registering with the other chute and adapted to receive respectively coins or checks of different sizes, 55 a plunger, means whereby rotation of said shaft will actuate said plunger, a ratchet wheel on said shaft, a rock shaft, a pawl carried by said rock shaft and adapted to engage said ratchet wheel, and means carried 60 by the rock shaft and adapted to be engaged

by a coin or check to rock said shaft and trip said pawl.

2. A device of the kind described comprising a reciprocating plunger, said plunger having a rack portion, a rotatable shaft provided with a gear wheel adapted to engage said rack portion, chutes adapted to receive checks or coins said chutes terminating above said shaft and said shaft having coin or check receiving openings therein, a double ratchet on said shaft, a rock shaft, tripping fingers carried by said rock shaft and adapted to be engaged respectively by checks or coins seated in the shaft openings, a double pawl adapted to engage opposite sides of 75 said double ratchet, said pawl being mounted on said rock shaft, a vertically movable rod connected to one of said tripping fingers, stops carried by said rod and adapted to engage said plunger, check actuated means for 80 removing one of said stops from the path of the plunger, and means for returning said stop to normal position after engagement of the other stop by the plunger.

3. A device of the kind described comprising two coin chutes, a rotatable shaft in alinement therewith having coin receiving openings, a reciprocating plunger, rotation of shaft operating said plunger, a double ratchet on said shaft, a rock shaft, a double 90 pawl on the rock shaft adapted alternately to engage oppositely arranged teeth on said ratchet, fingers carried by the rock shaft and the paths of coins in said openings, a vertically movable rod connected to 100 one of said fingers, a movable stop on said rod normally in the path of the plunger, a second stop on said rod, means actuated by a coin in one of said openings only for swinging the first mentioned stop out of 105 the path of the plunger, and means for returning said stop to normal position.

4. The combination with a reciprocating plunger, a rotatable shaft, said plunger having a rack portion thereon, a gear on said 110 shaft engaging said rack portion, a double ratchet on the shaft, a coin chute, a groove on the shaft in alinement with said chute, a second chute adapted to receive a larger coin than the first mentioned chute, an 115 opening in said shaft adapted to receive and hold the larger coin, a rock shaft, a double pawl fixed on the rock shaft the members of which alternately engage said double ratchet, tripping fingers fixed on the rock 120 shaft and adapted to be tripped respectively by coins held by the shaft upon partial rotation of the shaft in one direction, a vertically movable rod pivotally connected to one of the tripping fingers, a plunger 125 stop carried by the upper end of the rod, a movable stop carried by the intermediate portions of the rod a lever adapted to be engaged by the larger coin only, a rod connected to said lever means connecting said

rod with said second mentioned stop for swinging the same out of the path of the plunger on movement of the lever by the coin, a claw carried by the tripping finger 5 engaged by the larger coin and means carried by the last mentioned rod and adapted to be engaged by said claw for returning said rod and lever and the second mentioned

stop to normal position when the plunger engages and lifts the first mentioned stop. 10

In testimony whereof I affix my signature in the presence of two witnesses.
